US00D785688S

(12) **United States Design Patent** (10) **Patent No.:** **US D785,688 S**
(45) **Date of Patent:** **** May 2, 2017**

(54) **ARM FOR A ROBOT**

- (71) Applicant: **Yoshihiro Matsuda**, Seto (JP)
(72) Inventor: **Yoshihiro Matsuda**, Seto (JP)
(73) Assignee: **Toyota Jidosha Kabushiki Kaisha** (JP)
(**) Term: **15 Years**
(21) Appl. No.: **29/547,945**
(22) Filed: **Dec. 9, 2015**

(30) **Foreign Application Priority Data**

- Jul. 9, 2015 (JP) 2015-015313
(51) **LOC (10) Cl.** **15-99**
(52) **U.S. Cl.**
USPC **D15/199**
(58) **Field of Classification Search**
USPC D15/199; D21/578-583, 621, 622
CPC B25J 9/044; B25J 9/102; Y10T 74/20305

(57) **CLAIM**

The ornamental design for an arm for a robot, as shown and described.

DESCRIPTION

FIG. 1 is a perspective view of an arm for a robot showing my new design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

1 Claim, 7 Drawing Sheets
